UNITED STATES PATENT OFFICE

155,953

DESIGN FOR A PICTURE FRAME

La Verne J. Winslow, Pasadena, Calif.

Application July 30, 1948, Serial No. 147,847

Term of patent 14 years

(Cl. D29—20)

To all whom it may concern:

Be it known that I, La Verne J. Winslow, a citizen of the United States of America, residing in the city of Pasadena, in the county of Los Angeles, State of California, have invented a new, original, and ornamental Design for a Picture Frame, of which the following is a specification, reference being had to the accompanying drawing, forming a part thereof.

I claim:

The ornamental design for a picture frame, substantially as shown.

LA VERNE J. WINSLOW.
